UNITED STATES PATENT OFFICE.

PHILIP H. SMITH, OF PAWLING, NEW YORK.

AEROPLANE.

1,110,355.

Specification of Letters Patent. Patented Sept. 15, 1914.

Application filed October 7, 1913. Serial No. 793,790.

To all whom it may concern:

Be it known that I, PHILIP H. SMITH, citizen of the United States, and a resident of Pawling, Dutchess county, State of New York, have invented certain new and useful Improvements in Aeroplanes, of which the following is a specification.

The object of my invention is to prevent the precipitate descent of an aeroplane in case of motor-failure, breakage of parts, or loss of control under ordinary conditions of use; and the invention consists in the construction and arrangement of parts described and claimed specifically, a distinctive feature being the provision of an auxiliary safety plane capable of release and independent action as related to the main plane, or planes, of the apparatus all as hereinafter fully set forth.

In the accompanying drawings, Figure 1, represents more or less diagrammatically and symbolically a biplane equipped according to my invention, and presumably traveling a horizontal direction or substantially so; Fig. 2, a similar view showing the biplane tilted at an angle of forty five degrees and the auxiliary safety plane in independent action; Fig. 3, is a top view of my auxiliary safety plane; Fig. 4, is a sectional elevation upon a larger scale, of means for controlling my auxiliary safety plane, the latter being represented in its lowest or normal position and adjacent parts only of the biplane being shown; Fig. 5, is a section taken upon plane 5—5 Fig. 4, looking downward; Fig. 6, is a top view of the auxiliary safety plane rudder expanded; Fig. 7, is a view of the auxiliary safety plane released and at the top of the mast; Fig. 8, a like view illustrating the re-locking of the auxiliary safety plane prior to its descent into normal position; Fig. 9, is a detail of means for limiting the play of the auxiliary safety plane; Fig. 10, a top view with the parts in the positions shown in Fig. 8, partly broken away; Fig. 11, is a sectional elevation upon a larger scale of the upper extremity of the mast illustrating means for effecting the parallelism of the auxiliary safety plane with relation to the fixed plane or planes, the lifting pawl being shown in its highest position; Fig. 12, is a similar view showing the lifting pawl in its lowest position.

In Figs. 4, 7 and 8 the axis s' of the aux-

iliary safety plane $s-s$, is shown in section, 55 the near half of the plane being omitted.

I have herein shown and described my invention as applied to a biplane, although it is applicable to a monoplane or any conceivable form of aeroplane, as may be found most expedient, so that I do not limit myself to the identical form and construction of parts herein shown, since various modifications in detail may be resorted to without departing from the spirit and intent of my 60 invention in this respect.

With this understanding A, represents symbolically an aeroplane of any ordinary or well known construction provided with the parallel planes a, a' , and rear control a^2 , 70 the motor, propellor and other details being omitted.

M is a tubular mast supported on the main frame-work of the apparatus at right angles to the fixed planes a, a' ,—said mast being 75 positioned centrally and forward,—preferably in close proximity and to the rear of the seat of the aviator.

Normally my auxiliary safety plane s, s , occupies a position parallel to and above the upper fixed plane a , as shown in Figs. 1 and 4 and being normally locked in such position constitutes essentially a supplemental plane of maintenance acting in conjunction with the main plane or planes below to sustain the aeroplane in its flight. Hence, if used on a biplane it practically gives the effect, under normal conditions, of a triplane; or if used on a monoplane it converts the latter in some respects, as for normal 80 flying, into a biplane,—the superficial area of auxiliary safety plane s, s , being of course made relatively proportionate in order to attain the results desired. Under adverse 85 conditions of flight however the main function of the auxiliary plane s, s , is to render the aeroplane self-righting and safe in regaining or descent. Thus in case of motor failure, the breakage of other parts, or loss of control for any reason, the release of the auxiliary safety plane s, s , obviates all danger of headlong descent, turning over or collapse, by allowing said auxiliary plane to automatically adapt itself to the air pressure 90 in such manner as to turn the aeroplane to 105 face the wind pressure, thereby retarding descent and enabling the aviator to regain control of the apparatus.

To this end I secure my auxiliary safety plane s, s , to a pivotal axis s' , which is longitudinally parallel to the fixed plane a below, but which under certain conditions is free to turn within prescribed limits so that the said auxiliary safety plane s, s , when free may adapt itself to wind pressure under the guidance and control of a fixed rudder r , attached to the frame F . This frame F , 10 comprises an upper sleeve f , and a lower sleeve f' , both slidably and rotatably mounted upon the cylindrical mast M ,—said sleeves f , and f' being connected with and affording support for the bracket members f^2, f^3 and f^4, f^5 respectively. Upon the bracket members f^2, f^3 the axis s' , of the auxiliary safety plane s, s , is mounted in bearings s'', s'' , while the rear bracket members f^4, f^5 support the rudder r , and the 15 rock lever b , which latter is pivotally attached as at f^6 . A stop b' , on the bracket member f^5 limits the motion of the rock lever b , in one direction; and a pressure spring b^2 interposed between the lower part 20 of said rock lever b and the sleeve f' tends constantly to thrust and maintain said lever in contact with said stop b' , as shown in Figs. 7 and 8, in which position the shoulder b^x on the lever b , is adapted to engage with 25 and support the end of the arm s^3 attached rigidly to the axis s' of the auxiliary plane s, s . When the auxiliary plane s, s and frame F descend to the lower normal position the lower end of the lever b contacts 30 with a cam surface c , thereby rocking the lever b against the resistance of the pressure spring b^2 , as shown in Fig. 4 and thus releasing the arm s^2 .

s^3 is a bolt arm also rigidly secured to 40 the axis s' of the auxiliary plane s, s , and formed at its lower extremity with a shoulder s^4 , for engagement with a spring belt d , when the frame F is in its lowest position as shown in Fig. 4,—the two arms s^2 and s^3 45 extending at right angles to each other or substantially so.

A spring s^{22} , attached at one end to the arm s^2 and at the other to the sleeve f' , tends 50 constantly to depress the arm s^2 and to release the arm s^3 from the spring bolt d , and to counteract this tendency, and to lock the frame F in its lowest position, another spring bolt e , or equivalent mechanical expedient is provided, to be retracted either 55 manually as by the handle e' , or automatically when the aeroplane assumes a dangerous inclination by means of the gravity release G . This gravity release G , consists of a weighted pendulum g , suspended from 60 a universal joint g' and provided with cross arms g^2 connected by cords g^3 or equivalent means, with the retractor g^4 , as shown in Fig. 4,—the slack of the connections g^3 being sufficient, say, to allow of the inclination 65 of the aeroplane to any degree less than 45° ,

without causing the gravity release G to retract the bolt e .

The parts being in the normal positions shown in Fig. 4, the withdrawal of the bolt e , causes the spring s^{22} , acting upon the arm s^2 to incline the auxiliary safety plane s, s , at an angle with relation to the fixed or main plane a , or planes a, a' , and this degree of inclination may be limited, for instance, by a stop h , consisting of a bent arm secured 70 to the axis s' and arranged to contact with a member f^2 of the frame F , so as to limit the divergence of the auxiliary plane s, s , to say, an angle of 45° as related to the main plane or planes. By making this stop arm 75 h , adjustable upon the axis s' , as by a set screw h' , as indicated in Fig. 9 it is obvious that this degree of divergence of the auxiliary plane s, s , may be regulated and limited as desired; and by the use of a similar stop h^2 , the parallelism of the planes 80 may be attained with accuracy.

The effect of the release of the auxiliary safety plane s, s , is to cause it, under the control of the rudder r , to present resistance 90 to the air pressure, and this resistance causes the frame F to slide up the mast M until the upper collar f , contacts with the cap m , at the top of the mast. Hence the auxiliary plane s, s , acting through the mast as a 95 lever, tends to deflect the aeroplane from its downward course and to bring its fixed main plane or planes again into action in alignment with the air pressure or substantially so, so as to sustain the apparatus more 100 or less in its descent; if not to bring it again under the control of the aviator, for even if failing in this latter respect the auxiliary plane s, s , if made of appropriate superficial area will divert the aeroplane sufficiently 105 from a head-long vertical course to cause it to describe a curve and descend in comparative safety. The mast M not only thus acts as a lever to apply the resistance afforded by the released auxiliary plane s, s , but it 110

also serves as a track or guide to remove the auxiliary plane from the immediate vicinity of the fixed plane below, to afford freedom of action and available air pressure or resistance. Furthermore the frame F , 115 when released from the lower normal position shown in Fig. 4, is free to rotate upon the mast M under the guidance and control of the rudder r , so that the auxiliary plane s, s , will automatically face the line of greatest resistance or air pressure and thereby tend constantly to bring the aeroplane into alignment. And in order to guard against all contingencies of accident and disaster, and to counteract all possible tendency to 120 fall backward or tail-on, I form the rear portion of the rudder r , in two sections r', r' , hinged to the main portion r , so that in case of back action or pressure the said rear sections r', r' , will be spread apart tempo- 130

rarily against the stops r^2 , r^2 , as shown in Fig. 6, thereby causing the frame F to swerve to one side or the other and so to bring the auxiliary plane s , s , to face the wind and right the aeroplane.

When the auxiliary plane s , s , is used temporarily as an adjunct or supplementary means of control, as during gliding, exhibition maneuvers &c., or where the auxiliary plane has been used to counteract unfavorable atmospheric conditions and it is desirable to restore said auxiliary plane and its frame to the normal position and relationship shown in Figs. 1 and 4, this may be accomplished by again bringing said auxiliary plane s , s , into parallelism with the main plane or planes, under which conditions the auxiliary plane and its frame will settle by gravity into said normal position. To this end I provide a plane-setting device in the upper part of the mast M consisting essentially of a spring pawl or lifter i , pivotally mounted upon a traveling block or carrier i' , situated within the mast. The alinement of this carrier i' may be provided for in any suitable or desired manner. As shown in the drawings the mast is formed with longitudinal slots m' , m^2 , and the carrier i' , with lugs i^2 , i^2 , projecting into said slots so as to prevent the rotation of the carrier i' . The movement of the lifting pawl i on its block i' is limited by a pin i^3 on said block, said pin resting in concentric groove i^4 , in the lifter i , the ends of which slot act as shoulders to engage the pin as shown in Figs. 11 and 12,—the spring i^5 tending constantly to hold the lifting pawl i , in the position shown in Fig. 12. Attached to the lifting pawl i , is a cord or equivalent j , passing over a pulley j' mounted in the upper end of the mast, and down through the latter to a pulley j'' mounted in an opening in the lower part of the mast below the fixed plane a , as shown in Fig. 4, from which opening and pulley j'' , the cord j , may be led over another pulley j^2 so mounted as to bring the handle j^3 into convenient proximity to the aviator. Supposing the carrier i' to be in the lowest position as in Fig. 12 and the auxiliary plane s , s , and its frame F to be at the top of the mast M and held thereby air pressure due to the inclination of the auxiliary plane s , s , if the cord j , is pulled by means of the handle j^3 it will turn the lifting pawl i , against the resistance of the spring i^5 , until the point i^6 of said lifting pawl projects through the slot m' and will raise the carrier i' into the position shown in Fig. 11,—the point i^6 of the lifting pawl i , in its upward journey encountering the under side of the arm s^2 , and raising it into the position shown in Fig. 8 against the resistance of the spring s^2 . As the arm s^2 , is thus raised its end encounters and pushes back the lever b , against the resistance of the spring b^2 which latter when

the end of the lever has passed the shoulder b^3 , forces said shoulder b^3 under the end of said arm s^2 , thereby locking the auxiliary plane s , s , parallel in position to the fixed plane a , below, and also bringing the arm s^3 into position for engagement with the spring bolt d . The aeroplane being presumably sailing against and at right angles to the wind pressure, the frame F under the guidance of the rudder r , upon the release of the pull cord j , will descend by gravity in alinement or substantially so with the bolt d , and cam e , below, and to insure an accurate register and engagement of the parts I prefer to make the lower portion of the sleeve f' V shaped to contact with a correspondingly formed seat v , as shown in Fig. 4, so that any slight variation in alinement during descent will be corrected. At the completion of the descent of the frame F &c., the curved side of the shoulder s^4 on the lever s^3 forces said shoulder into engagement with the spring bolt d , and at the same time the cam e , acting on the lower end of the lever b , releases the arm s^2 from the latter, so that upon the withdrawal of the bolt e , the auxiliary safety plane s , s , will be again released and free to adapt itself instantly to wind pressure and to act independently of the main or fixed plane or planes as hereinbefore set forth.

As hereinbefore intimated I do not limit myself to the identical form and construction of details and devices herein shown, the same being used to illustrate the practical application of my invention, and being designed to cover equivalent mechanical expedients as well as modifications within the scope and intent of my invention.

It is to be noted that my auxiliary safety plane and its connections are entirely independent of, and do not interfere with, the ordinary control of the aeroplane; and that under normal fixed conditions the auxiliary plane adds to the sum total of the sustaining surface, while the auxiliary rudder tends to stability of alinement and motion. Furthermore a single movement of the hand of the aviator is sufficient to immediately release the auxiliary safety plane; and a single movement is likewise all that is necessary to reset the auxiliary plane and restore it to its normal position. And if the aviator is careless or incapacitated for any reason, in case of the dangerous inclination of the aeroplane my automatic release will insure safety.

While it may be desirable under ordinary conditions of use that the auxiliary plane be held by positive means normally parallel and in proximity to the main plane surface, it is also capable of free use and play unrestrictedly on the mast as automatic means for counteracting the effects of sudden variations in pressure or direction of air cur-

rents, to facilitate gliding &c., and as a constant safety medium not dependent on manual or mechanical release, in which case a coiled spring x , may be arranged in conjunction with a stop x' , as in Fig. 3, to tend constantly to hold the auxiliary plane parallel to the main plane, but to yield under excess of air pressure upon dangerous inclination of the aeroplane,—the distinctive feature of my invention consisting essentially in the use, on an aeroplane in conjunction with the fixed plane surface thereof, of an independent auxiliary plane movable upon its axis to conform to air resistance, in connection with a rudder arranged to present said auxiliary plane to the direct line of air pressure.

What I claim as my invention and desire to secure by Letters Patent is,

20. 1. In combination, an aeroplane, a mast carried by said aeroplane, a frame slidably mounted on said mast, releasable means for locking said frame in normal position, an auxiliary plane pivotally mounted on said frame, releasable means for locking said auxiliary plane parallel to the main plane surface, and a rudder mounted on said frame.

2. In combination, an aeroplane, a mast carried by said aeroplane, a frame slidably mounted on said mast, releasable means for locking said frame in normal position, an auxiliary plane pivotally mounted on said frame, releasable means for locking said auxiliary plane parallel to the main plane surface, and a rudder mounted on said frame; said rudder being formed with hinged expandable rear sections, for the purpose described.

3. In combination, an aeroplane, a mast carried by said aeroplane, a slidable frame mounted on said mast, an auxiliary plane pivotally mounted on said frame, a rudder mounted on said frame, releasable means for retaining said frame in its normal position, and means for automatically releasing said frame consisting of a spring bolt, a gravity pendulum supported upon a universal joint formed with lateral arms, and flexible means connecting said arms with said spring bolt whereby when the aeroplane is tilted at a prescribed angle the auxiliary plane will be released for the purpose described.

4. In combination, an aeroplane, a mast carried by said aeroplane, a frame slidably mounted on said mast, releasable means for locking said frame in normal position, an auxiliary plane pivotally mounted on said frame, releasable means for locking said auxiliary plane parallel to the main plane surface, a rudder mounted upon said frame, and means for turning said auxiliary plane

into parallelism with the main plane surface after its release, for the purpose set forth.

5. In combination, an aeroplane, a mast mounted thereon, a frame slidably on said mast, releasable means for securing said frame in its normal position, an auxiliary plane mounted upon an axis pivotally supported on said frame, locking arms secured to said axis, and a spring bolt and cam release arranged to act in conjunction with said arms to lock one while releasing the other, thereby setting the parts in such manner that the auxiliary plane may be released by the withdrawing of a single bolt as and for the purpose set forth.

6. In combination, an aeroplane, a mast carried thereby extending substantially at right angles to the fixed plane surface, a frame slidably mounted on said mast, releasable means for locking said frame in its normal position adjacent the fixed plane surface, an auxiliary plane pivotally mounted on said frame, and means for automatically releasing said auxiliary plane axially upon the release of the said frame.

7. In combination, an aeroplane, a mast carried thereby extending substantially at right angles to the fixed plane surface, a frame slidably mounted on said mast, releasable means for locking said frame in its normal position adjacent the fixed plane surface, an auxiliary plane pivotally mounted on said frame, means for automatically releasing said auxiliary plane axially upon the release of the said frame, and means for bringing said auxiliary plane into parallelism with the fixed plane surface and automatically locking it in such position, for the purpose set forth.

8. In combination, an aeroplane, a mast carried thereby, a frame slidably mounted on said mast, releasable means for locking said frame in its normal position at the bottom of said mast, an auxiliary plane pivotally mounted on said frame, and means for limiting the inclination of said auxiliary plane when released axially, for the purpose described.

9. In combination, an aeroplane, a mast carried thereby, a frame slidably mounted on said mast, releasable means for locking said frame in its normal position at the bottom of said mast, an auxiliary plane pivotally mounted on said frame, and adjustable means for regulating the prescribed inclination of said auxiliary plane when released for the purpose described.
